BURNER

Ollison Craig, Worcester, Mass., assignor to Riley
Stoker Corporation, Worcester, Mass., a cor-
poration of Massachusetts

Application June 19, 1942, Serial No. 447,623

10 Claims. (Cl. 122—235)

This invention relates to burners, and more particularly to burners for use with fluent fuels, such as blast furnace gas, and having provision for introducing fuel and air into a furnace between spaced upright water wall tubes.

Blast furnace gas has a comparatively small heating value per unit volume, and it is therefore necessary to provide a large flow area for the discharge of the gas into the furnace in order to avoid excessive gas velocities. Because of the obstruction afforded by the water tubes, it is a difficult matter to provide the flow area required for large burner capacities. It is also very important to effect a thorough mixing of the fuel and air in order that combustion may take place rapidly and a comparatively short flame may be obtained. Blast furnace gas usually carries a considerable quantity of solid impurities in suspension, and when this material comes in contact with hot surfaces it adheres thereto. The removal of such deposited material from prior burners has been a serious problem.

It is accordingly one object of the invention to provide a burner which will be capable of discharging large volumes of fluent fuel and combustion air without excessive velocity, particularly in connection with furnaces having water wall tubes between which the fuel must pass.

It is a further object of the invention to provide a burner which will produce a comparatively thorough mixing of the fuel and air as these elements enter the furnace.

It is a further object of the invention to provide a burner constructed largely of metal parts which are effectively shielded from the furnace heat by means of water tubes.

It is a further object of the invention to provide a burner particularly suitable for use with blast furnace gas and so constructed that solid matter which may be deposited in the gas passages can be readily cleaned therefrom.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a vertical section through a blast furnace gas burner, the section being taken on the line 1—1 of Fig. 3;

Fig. 2 is a section on the line 2—2 of Fig. 3;

Fig. 3 is a section on the line 3—3 of Fig. 1; 55

Fig. 4 is an elevation of the burner from the furnace side thereof, on a reduced scale;

Fig. 5 is a section on the line 5—5 of Fig. 1;

Fig. 6 is an enlarged fragmentary view in section on the line 6—6 of Fig. 3;

Fig. 7 is a section on the line 7—7 of Fig. 6; and

Fig. 8 is a section on the line 8—8 of Fig. 6.

The embodiment illustrated comprises a furnace wall 10 which is protected on the furnace side by a row of spaced upright water wall tubes 11. Water is circulated through these tubes in any suitable manner so that they may serve to generate steam by the absorption of radiant heat from the furnace. The wall 10 is provided with a rectangular opening 12 for the reception of a similarly shaped burner casing 14 which extends forwardly from the wall and is preferably constructed largely of rolled metal sheets or plates suitably welded together. The portions of the water tubes 11 which extend across the opening 12 are arranged in groups, with two tubes in each group, so that the tubes are positioned with alternately close and wide spacing in a common plane, as best shown in Fig. 3. Preferably the tubes in each group are substantially in contact with each other. In order that this may be done while maintaining a substantially uniform spacing of the tubes over the remainder of the wall 10, the required tubes may be formed with reverse bends 15 above and below the burner opening 12, as shown in Fig. 4. The rear portion of the casing 14, which is located within the opening 12, is lined with comparatively thick cast plates 16 of a suitable heat-resisting metal. Preferably this portion of the casing is offset outwardly by an amount equal to the thickness of the plates 16, so that the inner surfaces of the plates will be flush with the inner surfaces of the casing extending forwardly therefrom.

The interior of the casing 14 is divided by means of vertical longitudinally extending partitions 18 and 19 to provide a series of air passages 20 and gas passages 21 through which the elements of combustion flow rearwardly and enter the furnace between the water tubes 11. As best shown in Fig. 3, each partition 18 is located in substantial alignment with one group of the water tubes 11, while each partition 19 is located intermediate two of these groups. The air passages 20 alternate with the gas passages 21, there being one air passage and one gas passage discharging between each pair of adjacent tube groups. The front portions of the partitions are formed of rolled metal sheets or plates with their top and

bottom edges welded to the casing 14. The rear portions of the partitions 18 and 19 are formed of comparatively thick cast metal plates 23 and 24 respectively, of a suitable heat resisting metal. These plates are connected to the sheet metal adjacent the gas passages 21. As shown in Fig. 5, each of the plates 23 and 24 is made up of two sections connected by a ship-lap joint, to facilitate manufacture and assembly, and the top and bottom edges of the plates are fitted into grooves 25 in the plates 16. Gas is admitted to the fuel passages 21 through a gas inlet opening 26 in the bottom of the casing 14 near the front thereof, and air is admitted to the air passages 20 through an air inlet opening 27 in the top of the casing near the front thereof. Both the gas and the air are preferably supplied at a pressure above atmospheric, and the air is preferably pre-heated. The front end of each air passage 20 is separated from the gas inlet 26 therebeneath by an upwardly and forwardly sloping plate 29 which is lined on its rear face with refractory material 30. On the front wall of the casing 14 there are provided observation doors 32 aligned with the air passages 20 and cleanout doors 33 aligned with the gas passages 21.

The rear or discharge ends of the passages 20 and 21 are constructed to promote mixing of the fuel and air. As shown particularly in Fig. 3, the rear edges of the plates 24 are spaced forwardly from the row of water tubes 11, so that the fuel and air streams may intermingle before they pass rearwardly between the water tubes. This mixing is further promoted by means of rearwardly and laterally flaring deflectors 35 located between the rear edges of the plates 23 and the water tubes to form rearward extensions of the partitions 18. These deflectors are preferably made of a suitable heat-resisting cast metal, and as shown in Figs. 6 and 7 they are fastened to the plates 23 by means of bolts 36 which pass through rearwardly projecting lugs 37 on the plates, these lugs entering recesses 38 in the deflectors. In the rear surface of each deflector 35 there is provided a vertical groove 40 for the reception of the forwardly projecting flanges 41 of T-shaped clips 42 (Figs. 6 and 8) which are welded to the water tubes 11. Each flange 41 is provided with a vertical slot 43 therein for the reception of a transverse bolt 44 passing through the deflector 35. This construction maintains the desired relationship between the various parts without interfering with longitudinal expansion of the water tubes.

It will be noted from Fig. 3 that the air passages 20 are somewhat wider than the gas passages 21. These relative widths are preferably so selected that the kinetic energy of the air flowing in a passage 20, as represented by one-half the product of its mass by the square of its velocity, will be substantially equal to the kinetic energy of the gas flowing in an adjacent passage 21. This will avoid lateral deflection of the flames issuing into the furnace and ensure more effective mixing. In calculating the widths of these passages it will of course be necessary to take into consideration not only the weights of air and gas required per unit of time for proper combustion, but also the temperatures and specific gravities of these elements.

It will now be apparent that in the operation of the invention air and gas will flow rearwardly through the passages 20 and 21 respectively, and as they pass the rear edges of the plates 24 they

will begin to mix and combustion will start very shortly thereafter. This mixing will be greatly aided by the effect of the deflectors 35, which will direct the adjacent streams into laterally converging paths. These deflectors are well protected from the furnace heat by means of the water tubes 11. The various castings in the rear portion of the burner are well adapted to withstand such heat as is likely to reach them, and they can easily be replaced should occasion demand. The refractory material 30 will protect the walls 29 not only from the furnace heat but also from the heat of the combustion air, thereby minimizing the deposit of material from the gas stream on the front of these walls. Such deposits as form within the gas passages 21 can readily be scraped off by suitable tools inserted through the doors 33. This procedure is facilitated by the smoothness of the gas passage walls and the lack of projecting parts. The burner construction, particularly the arrangement of the water tubes, is such as to provide comparatively large areas for the discharge of air and fuel into the furnace. Consequently high operating capacities can be obtained without the long flames resulting from excessive discharge velocities.

Having thus described my invention, what I claim as new and desire to secure by Letters Patent is:

1. A burner for fluent fuel comprising a casing, a plurality of longitudinally extending parallel partitions dividing the interior of the casing into a series of rearwardly directed passages, and means to supply fluent fuel to certain of the passages and combustion air to other of the passages, the fuel passages alternating with the air passages, the rear edges of alternate partitions extending rearwardly a substantial distance beyond the rear edges of the intermediate partitions.

2. A burner for fluent fuel comprising a casing, a plurality of longitudinally extending parallel partitions dividing the interior of the casing into a series of rearwardly directed passages, and means to supply fluent fuel to certain of the passages and combustion air to other of the passages, the fuel passages alternating with the air passages, the rear edges of alternate partitions extending rearwardly a substantial distance beyond the rear edges of the intermediate partitions, and the rear portions of the said alternate partitions being shaped to deflect the adjacent streams laterally.

3. A burner for fluent fuel comprising a casing, a plurality of longitudinally extending upright partitions dividing the interior of the casing into a series of rearwardly directed passages, means to supply fluent fuel to certain of the passages and combustion air to other of the passages, the fuel passages alternating with the air passages, the rear edges of alternate partitions extending rearwardly a substantial distance beyond the rear edges of the intermediate partitions, and a water wall tube adjacent the rear edge of each of said alternate partitions to shield the same from radiant heat.

4. A burner for fluent fuel comprising a casing, a plurality of longitudinally extending parallel partitions dividing the interior of the casing into a series of passages, means to supply fluent fuel to certain of the passages and combustion air to other of the passages, the fuel passages alternating with the air passages, and rearwardly and laterally flaring deflectors adjacent the rear edges of alternate partitions and substantially aligned

with the said alternate partitions to promote mixing of the issuing streams of fuel and air.

5. A burner for fluent fuel comprising a rectangular casing constructed largely of rolled metal sheets, a lining of comparatively thick cast plates of heat-resisting metal in the rear portion of the casing and shaped to provide a series of opposed longitudinal grooves, a plurality of longitudinally extending parallel partitions dividing the interior of the casing into a series of 10 passages, the partitions having front portions of rolled metal sheets and rear portions of comparatively thick cast plates of heat-resisting metal which fit within the said grooves, and means to supply fluent fuel to certain of the passages and combustion air to other of the passages.

6. A burner for fluent fuel comprising a casing, a plurality of longitudinally extending upright partitions dividing the interior of the casing into a series of rearwardly directed passages, means to supply fluent fuel to certain of the 15 passages and combustion air to other of the passages, water wall tubes located adjacent the rear edges of alternate partitions, and rearwardly and laterally flaring deflectors in front of the tubes.

7. A burner for fluent fuel comprising a casing, a plurality of longitudinally extending upright partitions dividing the interior of the casing into a series of rearwardly directed passages, means to supply fluent fuel to certain of the 20 passages and combustion air to other of the passages, water wall tubes located adjacent the rear edges of alternate partitions, rearwardly and laterally flaring deflectors in front of the tubes, and means connecting the deflectors to the tubes.

8. A burner for fluent fuel comprising a casing, a plurality of longitudinally extending upright partitions dividing the interior of the casing into a series of rearwardly directed passages, means to supply fluent fuel to certain of the 25 passages and combustion air to other of the passages, water wall tubes located adjacent the rear edges of alternate partitions, rearwardly and laterally flaring deflectors in front of the tubes, clips welded to the front surfaces of the tubes, and means connecting the deflectors to the clips.

9. In combination with a furnace wall having a

rectangular opening therethrough, a row of spaced upright water wall tubes adjacent the furnace side of the wall, certain of the tubes crossing the opening and being arranged in groups with two closely spaced tubes in each group and wide spaces between the groups, a rectangular casing mounted in the opening and extending forwardly from the wall, upright partitions within the casing in substantial alignment with the tube groups, other upright partitions within the casing intermediate the first mentioned partitions with their rear edges spaced forwardly from the row of water tubes, the partitions forming a pair of longitudinally extending 30 passages leading to each of the said wide spaces, means to supply fluent fuel to one of the passages in each pair, means to supply combustion air to the other passage in each pair, and a rearwardly and laterally flaring deflector mounted directly in front of each group of tubes to promote mixing of the fuel and air.

10. In combination with a furnace wall having a rectangular opening therethrough, a row of spaced upright water wall tubes adjacent the furnace side of the wall, certain of the tubes crossing the opening and having reverse bends above and below the opening in the plane of the row to arrange the portions of the tubes adjacent the opening in groups with two closely spaced tubes in each group and wide spaces between the groups, a rectangular casing mounted in the opening and extending forwardly from the wall, upright partitions within the casing in substantial alignment with the tube groups, other upright partitions within the casing intermediate the first mentioned partitions with their rear edges spaced forwardly from the row of water tubes, the partitions forming a series of longitudinally extending passages leading to the 35 spaces between the tube groups, with two passages for each of the spaces, means to supply fluent fuel to certain of the passages and combustion air to other of the passages, the fuel passages alternating with the air passages, and a rearwardly and laterally flaring deflector mounted directly in front of each group of tubes to promote mixing of the fuel and air.

OLLISON CRAIG.
